A. A. HOWARD

ELECTRICAL TRANSFORMER

Filed March 7, 1925

FIG. 1.

FIG. 2.

FIG. 3.

Inventor:
Austin A. Howard,
By my son, Lee, Austin, Miles,
Feb 1925.

UNITED STATES PATENT OFFICE.

AUSTIN A. HOWARD, OF CHICAGO, ILLINOIS.

ELECTRICAL TRANSFORMER.

Application filed March 7, 1925. Serial No. 13,773.

To all whom it may concern:

Be it known that I, AUSTIN A. HOWARD, a citizen of the United States, residing at Chicago, in the county of Cook and State of Illinois, have invented a new and useful Improvement in Electrical Transformers, of which the following is a specification.

This invention relates to improvements in electrical transformers. One of the objects 10 of the invention is to provide a transformer which can be easily and cheaply made and which will be strong and durable. I have here shown the invention as embodied in a transformer such as is used in connection 15 with radio apparatus for the amplification of waves at radio frequency.

In making such transformers, two coils are employed, a primary coil and a secondary coil. These coils are arranged in inductive 20 relation to each other and must be supported properly in this position. By the use of my invention I am able to do this in a very simple manner.

By the use of my invention I am able to 25 produce a coil in which the dielectric losses are reduced, the static charges lessened, and the capacity of the transformer lowered.

Other features and advantages of my invention will appear more fully as I proceed 30 with my specification.

In that form of device embodying the features of my invention shown in the accompanying drawings, Figure 1 is a top plan view of a complete transformer, Fig. 2 is a view taken as indicated by the line 2 of Fig. 35 1, Fig. 3 is a top plan view of the dielectric or insulator support for the wires forming a part of the transformer, and Fig. 4 is a fragmentary vertical sectional view taken as indicated by the line 4 of Fig. 2.

As shown in the drawings, 10 indicates a cylindrical supporting member here shown as made of dielectric or insulating material such as fibre, bakelite, hard rubber or the like. This cylindrical member is virtually 45 a section of tubing with a relatively thick wall and provided with a plurality of slots 11 therethrough, the series of such slots extending around the entire circumference of the support. The slots 11, it will be noted, are not parallel to the axis of the support but each is slanted slightly from end to end as most clearly shown in Fig. 3. I have indicated the remaining portions of the cylindrical shell or support between the slots 50 11 by the reference numerals 12, 12, and it

will be noted that these remaining portions 12, 12 virtually constitute bars or strips upon which the wires are wound as will be explained more in detail hereinafter. 60

By cutting the slots 11 in the dielectric support 10, the dielectric losses are reduced, the static charges lessened and the capacity of the transformer lowered.

On the outer surfaces of the bars or strips 12, there are cut grooves 13, 13, the different cuts on said portions together constituting one continuous spiral groove on the outer surface of the member 10 except as said groove is interrupted by the slots 11, 11. 70 The turns of this groove 13 are spaced apart the distance at which it is desired to space the turns of the primary coil. The groove 13 is made with a depth substantially equal to the distance which it is desired to space the primary or inner coil from the secondary or outer coil. Obviously, the wall of the member 10 must be of sufficient thickness to permit the requisite depth of the groove 13 and still furnish sufficient strength to support the wires. 75

14 indicates the wire forming the inner or primary coil. This wire is wound in the bottom of the cuts 13 which, as stated above, together form a continuous spiral groove. 85 The wire is formed in a continuous spiral coil and bridges across the gaps 11, 11.

The wire 14 may be bare as shown or it may be insulated. Preferably the supporting member 10 is made of insulating material, as stated above, so that the wire 14 may be bare; and when such wire is used the turns are properly spaced and insulated from each other by the groove 13. 90

After the primary coil 14 has been wound on the support, there is wrapped around the same a sheet of any suitable material such as, for example, paper 15. This material covers the grooves 13. After this paper is in place there is wound thereon the secondary coil 16 here shown as consisting of insulated wire. The sheet of material 15 prevents the turns of the coil 16 from entering the grooves or cuts 13. As here shown, the wire 16 is insulated so that the turns thereof may be placed next to each other without there being electrical contact. 100

While I have shown and described certain embodiments of my invention, it is to be understood that it is capable of many modifications. Changes, therefore, in the construction and arrangement may be made 105 110

without departing from the spirit and scope of the invention as disclosed in the appended claims, in which it is my intention to claim all novelty inherent in my invention as broadly as possible in view of the prior art.

5 What I claim as new, and desire to secure by Letters Patent, is:

1. A device of the character described comprising; a cylindrical support having a spiral groove in its outer surface, said support also being provided with cut away portions, said cut away portions interrupting said spiral groove; a wire laid in the bottom of said groove and spanning said cut away portions, the depth of said groove being greater than the diameter of the wire laid therein; a sheet of material wound on said support and lying over said groove; and another wire wound on the outer surface of 10 said sheet material.

15 2. A device of the character described comprising; a cylindrical support having a spiral groove in its outer surface, said support also being provided with longitudinal slots or cut away portions, said slots or cut away portions interrupting said 20

groove; a wire laid in the bottom of said groove and spanning said slots or cut away portions, the depth of said groove being greater than the diameter of the wire laid 25 therein; a sheet of material wound on said support and lying over said groove; and another wire wound on the outer surface of 30 said sheet material.

3. A device of the character described comprising; a cylindrical support having a spiral groove in its outer surface, said support also being provided with slanting longitudinal slots or cut away portions, said slots or cut away portions interrupting said 35 groove; a wire laid in the bottom of said groove and spanning said slots or cut away portions, the depth of said groove being greater than the diameter of the wire laid 40 therein; a sheet of material wound on said support and lying over said groove; and another wire wound on the outer surface of 45 said sheet material.

Witness my hand and seal this 5th day of March, A. D. 1925.

AUSTIN A. HOWARD. [L. S.]
